UNITED STATES PATENT OFFICE.

CHARLES W. MCKIBBEN, OF HOUSTON, TEXAS.

MEANS FOR SEPARATING ASSOCIATED LIQUIDS.

Application filed April 8, 1928. Serial No. 100,526.

This invention relates to improvements in my Patent No. 1,276,387 for a "method of separating associated liquids", dated August 20th, 1918, covering the art of separating associated liquids, in which particles of one liquid are held or bound in mechanical suspension in another as in emulsions, for example, as crude petroleum and water.

This invention relates primarily to an improvement in the apparatus for accomplishing the separation of associated liquids by providing a transformer controlled valve in the emulsified oil supply pipe connected with the treater to afford a means whereby the treater will act automatically when potential changes occur between electrically energized electrodes when the path through the liquid changes in resistance by the interchange of oil and water as the process of separation progresses.

It is an object of this invention to provide an automatically controlled valve in the emulsified oil supply pipe leading to a treater casing forming a part of an apparatus used for the separation of associated liquids.

It is also an object of this invention to provide a control valve in the supply pipe of a treater casing, said valve adapted to be automatically governed by the motion of a movable secondary coil of a transformer forming a part of the apparatus necessary for the separation of associated liquids.

Another object of the invention is to provide an apparatus for separating associated liquids by providing a control valve in the emulsified oil supply pipe, which valve is automatically controlled by a transformer to cause the control valve to close and thereby shut off the supply of emulsified oil when the voltage in the treater drops and furthermore acting to automatically open the valve when the voltage is increased.

It is an important object of this invention to provide an automatically acting control for governing the supply of emulsified oil to a treater, thereby making the operation of said treater automatic when used in an apparatus adapted to produce an improved process for the separation of entrapped water from oil, or in other emulsions.

Other and further objects of this invention will be apparent from the disclosures in the specification and accompanying drawing.

The invention in a preferred form is illus-

trated in the drawing and hereinafter more fully described.

On the drawing:

The accompanying drawing illustrates a portion of a schematic arrangement of apparatus for the separation of liquids and including improved apparatus embodying the principles of this invention.

As shown on the drawing:

The reference numeral 1 indicates a pedestal having mounted thereon an alternating, substantially constant current transformer, designated as a whole by the reference numeral 2, and embracing a secondary coil 3 and a primary coil 4. One terminal of the secondary coil 3 is connected by means of a wire 28 to an electrode 7. The other terminal of the secondary coil 3 has a ground wire 26 connected thereto. The terminals of the primary coil 4 are connected to the terminals of an alternating current dynamo 27. A treater casing 5 is provided having an opening in the top thereof closed by means of an insulated support or block 6 through which an electric conductor or electrode 7 projects into the treater casing. Mounted axially within the lower portion of the treater casing is a second electrode in the form of a pipe 8 open at its upper end to permit an overflow of an emulsified oil into the interior of the treater casing 5. Connected in an opening in the lower portion of the treater casing 5 is one end of a goose-neck trap 9, the other end of which is integrally connected with an outlet pipe 10 leading to a storage tank not shown. Connected to the lower end of the treater and to the pipe 8 is a three-way union 11, one opening of which is closed by means of a removable plug 12. Leading from an emulsified oil storage tank is a supply pipe 13 having an elbow 14 connected therewith. Connected with the elbow 14 is a valve housing 15 containing a valve 16 connected to a valve stem 17. The valve housing 15 is connected by means of a pipe 18 to the union 11 on the lower end of the treater casing. Pivotedly connected to the upper end of the valve stem 17 is one end of a link 19, the other end of which is pivotally connected to a beam or arm 20 fulcrumed at 21 to a supporting collar 22 secured upon the supply pipe 13. Pivotedly connected to the second end of the fulcrumed arm 20 is a downwardly projecting arm 23, the lower

end of which is bent at an angle to afford a finger 24 which projects between the coils 3 and 4 of the transformer. A finger 25 projects from the arm 23 above transformer 5 coil 3.

The improved apparatus hereinbefore described forms a part of a general schematic as covered in my Patent No. 1,276,387, of August 20, 1918. The omitted portions of 10 the schematic referred to may be found properly described and illustrated in the above mentioned patent.

By applying a valve in the emulsified oil supply pipe as described any type of treater 15 may be used and operated to automatically treat emulsions at full load under constant alternating current by allowing the voltage to drop or vary as the nascent state of the ohmic factor changes when emulsions are 20 being treated. The constant current transformer 2 is provided with a shiftable counterweight 29 adjustable on a graduated arc 30 to regulate the movement of the transformer coil 3 to cause the same to operate 25 the valve to either shut off the oil supply from the pipe 13 or open said valve to permit the supply of emulsified oil to again take place. In the actual treating of the emulsified oil the movable transformer coil 3 is 30 adapted to move up or down, thereby causing automatic operation of the valve 16 which controls the supply of emulsified oil to the treater casing 5. By placing the control valve in the supply pipe 13 with said 35 valve governed by the operation of the movable transformer coil 3 it will be seen that the action of the treater is automatic. If, for example, a large quantity of water is contained in the emulsion the movable transformer 40 coil 3 would rise and the voltage to the treater would rise, thereby tending to cause a short circuit in the treater; at this point in the operation the upward movement of the transformer coil 3 would engage the 45 arm 25, thereby causing the control valve 16 to close and stop the admission of emulsified oil to the treater. With the supply of emulsified oil cut off, the treater is permitted to 50 treat out or act on the liquid within the treater casing, after which the transformer coil 3 would go down, thereby increasing the voltage and causing the valve 16 to open and admit more emulsified oil into the treater.

55 It will thus be seen that in the practical working of the system that when real bad oil is supplied through the pipe 13 that said

oil tends to short circuit the treater, so to speak, causing the voltage to drop, due to the fact that the treater cannot handle the 60 fluid unless it is temporarily shut off. With the use of the control valve 16 governed by the operation of the movable transformer coil 3 the action of the treater is made automatic to take care of different kinds or 65 grades of emulsified oil. It will be understood that the improved scheme may be applied to any type of treater, thereby making it possible to automatically treat emulsions at full load and handle the same efficiently, 70 with the current remaining constant by permitting variations in the voltage as emulsions are being treated.

I am aware that many changes may be made and numerous details of construction 75 may be varied through a wide range without departing from the principles of this invention and I therefore do not purpose limiting the patent granted hereon otherwise than necessitated by the prior art. 80

I claim as my invention:

1. In a system of apparatus for the separation of associated liquids, the combination with a treater device forming a part of said system, of an emulsified oil supply pipe connected with said treater device, a transformer mechanism having a stationary and a movable coil, a control valve in said supply pipe near said treater device, a pivotally supported beam, a link connecting said beam with said valve and operating means connected with said beam adapted to be actuated by the movement of the movable transformer coil to control the operation of the treater device. 95

2. In a system of apparatus for the separation of associated liquids, the combination with a treater and the electrically energized electrodes thereof, of an emulsified oil supply pipe connected with the treater, a valve in said supply pipe, a pivoted beam, a link connecting said valve with one end of said beam, a movable transformer coil forming part of said system of apparatus, an arm pivoted to the other end of said beam, fingers on said arm adapted to be contacted by said transformer coil, and means for controlling the operation of said movable transformer coil to cause the same to actuate said valve. 100

In testimony whereof I have hereunto subscribed my name.

CHARLES W. MCKIBBEN,
